(57) **CLAIM**

We claim the ornamental design for a gaming machine display, as shown and described.

DESCRIPTION

FIG. 1 is a front perspective view of a first embodiment of a gaming machine display showing our new design; FIG. 2 is a front view of the gaming machine display design shown in FIG. 1;

FIG. 3 is a back view of the gaming machine display design shown in FIG. 1;

FIG. 4 is a right view of the gaming machine display design shown in FIG. 1;

FIG. 5 is a left view of the gaming machine display design shown in FIG. 1;

FIG. 6 is a top view of the gaming machine display design shown in FIG. 1;

FIG. 7 is a front perspective view of a second embodiment of a gaming machine display showing our new design;

FIG. 8 is a front view of the gaming machine display design shown in FIG. 7;

FIG. 9 is a back view of the gaming machine display design shown in FIG. 7;

FIG. 10 is a right view of the gaming machine display design shown in FIG. 7;

FIG. 11 is a left view of the gaming machine display design shown in FIG. 7; and,

FIG. 12 is a top view of the gaming machine display design shown in FIG. 7.

In these drawings, the solid lines illustrate the claimed ornamental design, whereas the broken lines illustrate unclaimed environmental features and form no part of the claimed design.
